UNITED STATES PATENT OFFICE

123,608

DESIGN FOR A STIRRING APPARATUS

Myron J. Zimmer, Chicago, Ill., assignor to The
Edward Katzinger Company, Chicago, Ill., a
corporation of Illinois

Application April 19, 1940, Serial No. 91,771

Term of patent 14 years

To all whom it may concern:

Be it known that I, Myron J. Zimmer, a citizen of the United States, residing at Chicago, in the county of Cook and State of Illinois, have invented a new, original, and ornamental Design for a Stirring Apparatus, of which the following is a specification, reference being had to the accompanying drawing, forming a part thereof.

Fig. 1 is a side elevational view of a stirring apparatus, showing my new design, a part of the lower portion being shown broken away.

Fig. 2 is a similar view, with the bowl portion shown in dotted lines in Figs. 1 and 3 being omitted for convenience of illustration, and with the apparatus turned through an angle of 90

degrees, and wherein a continuation of the solid line detail portion of the driving gear is represented by broken lines.

Fig. 3 is a top plan view of Fig. 1, and wherein a continuation of the solid line detail portion of the driving gear is represented by broken lines.

The dominant features of my design reside in the portion shown in solid lines and lines representing continuation of the solid line detail portion of the driving gear.

I claim:

The ornamental design for a stirring apparatus, substantially as shown and described.

MYRON J. ZIMMER.
